STRAND WINDING DEVICE

William H. Taylor, Pawtucket, R. I., assignor to
 The Clark Thread Company, Newark, N. J., a
 corporation of New Jersey

Application November 8, 1941, Serial No. 418,373

3 Claims. (Cl. 242—26)

This invention relates to a device for winding a strand on a bobbin, especially for the purpose of obtaining a strand mass on the bobbin having a tapered configuration at the end of said mass opposite the base of the bobbin.

One of the problems met in mechanisms for this purpose is lack of satisfactory control. For example, in mechanisms for the production of a straight taper, the absence of such control leads to uncontrolled irregularity of the tapered end, with resultant unmarketability or detraction from the marketability of the product.

It is an object of the present invention to devise improved mechanism to effect such adequate control. Further advantages and disadvantages will appear from the subsequent description taken in conjunction with the drawings, in which:

Fig. 1 is a plan view showing the parts in position at the beginning of the strand winding operation;

Fig. 2 is an end view corresponding to Fig. 1;
 Fig. 3 is a side elevation;

Fig. 4 is a plan view showing the parts in position at or near the end of the winding operation;

Fig. 5 is an end view corresponding to Fig. 4;

Fig. 6 is a plan view, partly in section, on the line 6—6 of Fig. 3.

Various conventional strand winding machines are well known, wherein a traverse frame carrying traverse mechanism including a thread guide moves radially in relation to a bobbin mounted to rotate with and axially along a revolvably mounted arbor. In such conventional machines, a thread guide may be mounted on a bracket carried by a traverse rod having a horizontal axis. The rod is horizontally reciprocated by a shoe member which is given a horizontal reciprocating motion by a part thereof which rides in a groove of an eccentric wheel. The said eccentric wheel is pivotally or rockably mounted on a shaft which carries the traverse frame including the traverse bar, thread guide, and counterweight. As the strand mass builds up on the bobbin, the entire frame undergoes a radial movement actuated by the thread guide bearing against the said strand mass. The thread guide and traverse bar are therefore mounted, not only to reciprocate horizontally and axially in relation to the axis of the bobbin, but also for radial movement transverse to the axis of the bobbin.

The present invention may advantageously be applied to such conventional strand winding machines and therefore the mechanism and operation of the latter need not be described and shown

in detail except in so far as to show the relationship of the construction and operation thereof to the construction and operation of the present invention.

5 In accordance with said invention, a hollow conical member 1 is provided having an axis coinciding with the axis of the arbor 2 and bobbin 3 mounted thereon. This conical member 1 is mounted to rotate with the arbor 2 and to move 10 axially along the mandrel 35 and is adapted to impart this axial movement to the bobbin 3 mounted on the arbor 2. The conical member 1 has an internal surface 4 and an external surface 5. In order that the conical member 1 may be 15 given its axial movement in consonance with the radial movement of the thread guide 18 and traverse frame 8 to produce the desired taper in the thread mass, means are provided which slidably engage each of the surfaces of the conical member. This means is mounted on the traverse frame 8 for radial movement therewith and, through the cooperation of this means and the conical member 1, the radial movement of the traverse frame 8 produces simultaneous axial 20 movement of the said conical member 1 and bobbin 3. The means referred to may comprise a yoke 10 having legs 11, 12 straddling the edges of the conical member 1, the said yoke 10 being secured to the traverse frame for radial movement therewith and the yoke 10 may be provided with adjustable parts slidably engaging both the internal and external surfaces of said conical member and being thereby adapted to move said member and bobbin axially along the arbor on 25 which the bobbin is mounted simultaneously with the radial movement of the yoke member secured to the traverse frame for the purpose of securing the desired taper in the end of the upward mass opposite the base of the bobbin. As a result 30 of the engagement of both faces of the conical member by the means, as for example a yoke or its equivalent, secured to the traverse frame, the bobbin 3 may be given a controlled axial movement along the arbor 2 on which it is mounted at 35 a uniform rate free from any backlash or other uncontrolled movement tending to produce uncontrolled irregularity in the desired taper.

It will be understood that any such uncontrolled movement of the bobbin is reflected in an uncontrolled contour of the taper and, as already stated, it is one object of the present invention to overcome this lack of control.

Referring now more particularly to the details of a particular embodiment of the principles of the present invention, certain parts of a conven-

tional strand winding machine are shown including parts of a traverse frame. These include a traverse bar 15 and a bracket 16 carrying the thread guide 18. The traverse frame as a whole is pivoted to rock about the shaft 20 which carries an eccentric wheel (not shown), which in turn imparts to the traverse bar 15 a reciprocating movement axially in relation to the axis of the bobbin, the frame carrying the conventional counterweight 21, as shown more particularly in the end views shown in Figs. 2 and 5. The strand 23 is presented to the strand mass 24 on the bobbin 3 by first passing over a guide roll 22 and then through the thread guide 18 which bears against the strand mass. As the 15 diameter of the latter increases during the winding operation, the traverse frame rocks outwardly and radially about its horizontal pivot 20.

To the drive shaft 25 of the said conventional machine there is secured the mandrel 35 by 20 means of an integral dowel pin 26 having a threaded end 27, these parts engaging corresponding recessed portions in the said shaft. On this mandrel 35 there is mounted, to move 25 slidably thereon, the hollow conical member 1 having a sleeve portion 28 carrying a slot 29 which engages a pin 30 on the mandrel 35 to limit the movement of the sleeve 28 axially of the mandrel 35 and to cause the sleeve 28 to rotate with the mandrel 35. The axis of the conical portion 1 coincides with the axis of the mandrel 35 and said conical portion 1 has an inside 30 surface 4 and an outside surface 5. Into the cylindrical recess 31 in the conical member is frictionally driven one enlarged end of the bobbin carrying arbor 2, the major portion of said arbor 2 having a reduced diameter, as shown clearly in Fig. 6. From this portion of the reduced diameter a part is cut out to permit the mounting 35 therein of a spring member 32 by means of the screws 33, the heads of which fall slightly below the surface of this reduced diameter portion of the arbor 2. By means of this spring mounting the bobbin 3 may readily be slipped over the arbor 2 and frictionally mounted thereon to rotate with the arbor conical member and mandrel, and to move axially along said arbor under the axial thrust of said conical member. The base of the bobbin may be separated from the 40 conical member by the washer 36 which, if desired, may be made integral with the conical member.

In order to impart axial movement to the conical member, means are provided to engage both the internal and external surfaces thereof, which means, when given a radial movement actuated by the swing of the pivotally mounted traverse frame, causes the conical member to move axially along the mandrel 35 in such controlled fashion as to produce the desired controlled straight line taper in the end of the thread mass. The axial movement of the conical member necessarily causes similar axial movement of the arbor 2 and the bobbin 3 mounted thereon and the latter therefore undergoes a movement axially of the mandrel. The particular means shown in the drawings for imparting this controlled axial movement to the conical member is the yoke 19. This may be formed of a metallic casting having the interior thereof hollowed out to form legs 11, 12 which straddle the edges of the hollow cone. Pins 38, 38A pass through holes in these legs and are adjustably mounted by means of set screws 39, 39A. The ends of the pins are appropriately beveled so

5 that beveled surfaces thereof simultaneously engage both the internal and external surfaces of the hollow conical member. The yoke member is adjustably secured to the plate 40 by means of a bolt 41 passing through the horizontal slot 42 in the lower part of the yoke 19 and secured in a threaded hole 41A in the plate 40.

In the operation of the device, thread is presented to the bobbin 3 and is wound thereon in a 10 so-called "open wind" produced by the reciprocating motion of the thread guide 18 carried by the bracket 16 mounted on the reciprocably mounted traverse bar 15. As the mass of thread increases in diameter, the thread guide 18, the bracket 16, the traverse bar 15, the plate 40, and the yoke member secured to the plate 40 (all constituting a part of the traverse frame) swing radially in relation to the axis of the bobbin 3 about the axis of the shaft 20 on which the traverse frame 8 and traverse mechanism are pivotally mounted. It will be understood that, while the thread guide has a combined axial and radial movement, the plate 40 and yoke 19 secured thereto have a movement only in one direction, to wit, a radial direction. This radial movement of the yoke member is converted into axial movement of the hollow conical member 1, mandrel 35, arbor 2, and bobbin 3 mounted thereon, by means of the pin 38 engaging the internal surface 4 of the hollow conical member. The simultaneous sliding engagement of the internal and external surfaces of the conical member by means of the pins 38 and 38A controls this axial movement, whereby a uniform axial movement of the mandrel 35, arbor 2, and bobbin mounted thereon in the direction of the arrow shown in Fig. 1 is secured and as a result the end of the strand mass requires the desired uniform taper, as illustrated in Fig. 4.

40 I claim:

1. In a machine for winding a strand mass on a bobbin, of the type wherein a traverse frame carrying a thread guide moves radially in relation to a bobbin mounted for coaxial rotation with and longitudinal axial movement in relation to a revolvably mounted mandrel; a hollow conical member having an axis coinciding with the axis of the mandrel and mounted to rotate with and move axially along said mandrel and being adapted to impart said axial movement to the bobbin, said conical member having an internal surface and an external surface; and means, slidably engaging each of said surfaces, mounted on said traverse frame for movement with said frame radially in relation to the axis of the bobbin, to move said conical member and bobbin axially simultaneously with said radial movement.

2. In a machine for winding a strand mass on a bobbin, of the type wherein a traverse frame carrying a thread guide moves radially in relation to a bobbin mounted for coaxial rotation with and longitudinal axial movement in relation to a revolvably mounted mandrel; a hollow conical member having an axis coinciding with the axis of the mandrel and mounted to rotate with and move axially along said mandrel and being adapted to impart said axial movement to the bobbin, said conical member having an internal surface and an external surface; and a yoke having legs straddling the edges of said conical member, secured to said traverse frame for movement with said frame radially in relation to the axis of the bobbin, said yoke having parts slidably engaging the internal and external 60 surfaces of said conical member and adapted to

move said member and bobbin axially simultaneously with said radial movement.

3. In a machine for winding a strand mass on a bobbin, of the type wherein a traverse frame carrying a thread guide moves radially in relation to a bobbin mounted for coaxial rotation with and longitudinal axial movement in relation to a revolvably mounted mandrel; a hollow conical member having an axis coinciding with the axis of the mandrel and mounted to rotate with and move axially along said mandrel and being adapted to impart said axial movement to

the bobbin, said conical member having an internal surface and an external surface; and a yoke having legs straddling the edges of said conical member and secured to said traverse frame for movement with said frame radially in relation to the axis of the bobbin, said yoke having pins adjustably mounted thereon, said pins slidably engaging the internal and external surface of said conical member and adapted to move said member and bobbin axially along said mandrel simultaneously with said radial movement.
